F. F. RAINSFORD

RUG

Filed Oct. 13, 1923

INVENTOR

Francis F. Rainsford

UNITED STATES PATENT OFFICE.

FRANCIS F. RAINSFORD, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

Application filed October 13, 1923. Serial No. 7,494. Term of patent 7 years.

To all whom it may concern:

Be it known that I, FRANCIS F. RAINSFORD, a citizen of the United States, residing at the city of Amsterdam, county of Montgomery, and State of New York, have invented a new, original, and ornamental Design for a Rug, of which the following is a specification, reference being had to the accompanying drawing, forming part thereof.

The drawing illustrates a portion of a rug, showing my new design. The entire rug is a repeat of the design shown in the drawing.

I claim:

The ornamental design for a rug, substantially as shown.

Dated, December 15th, 1923.

FRANCIS F. RAINSFORD.

Witnesses:

CHARLES A. KENWORTHY,
ALICE C. BROWNELL.
